ABSTRACT

An ice auger is formed of a body tube with ice-removing helix and a detachable blade, which has been provided with a supporting element fitting into the end of the body tube. The blade has been provided with one or several forks against the bottom of which the end of the helix rests, whereby the blade and the helix together form a continuous helical surface which has no fixing elements or shoulders slowing down the passage of the ice flow.

Fig. 1

Fig. 2

Fig. 3

Fig. 4

ICE AUGER

Prior art includes a number of different auger types in which the blade portion has been arranged to be detachable, and they have the feature in common that the blade, consisting of one or several parts, has been attached to the ice-removing helices by a screw or bolt attachment. They have, naturally, had the advantage that the blade, when placed in its case, has been protected against damage during transport, but they have the drawback that the insertion and fixing of the screws or bolts used for attachment has been a cumbersome and time-consuming work. Moreover, they have formed, together with the attachment shoulder, an obstacle slowing down the flow of ice, whereby the boring has been slowed down.

The aim of the present invention is to eliminate the drawbacks and to produce an ice auger the blade of which can be rapidly and easily detached and attached, which is a great advantage, for instance, when a damaged blade is replaced, and which auger has no elements slowing down the boring process. The invention is mainly characterized in that the blade has been provided with one or several forks against the bottom of which the end of the helix rests, whereby the blade and the helix together constitute a continuous helical surface which has no fixing elements or shoulders slowing down the passage of the ice flow.

The invention is described in closer detail in the following with reference to the attached drawings, wherein

FIG. 1 shows an embodiment of the invention in elevational view,

FIG. 2 shows the same, sectioned along the line II-II,

FIG. 3 shows the auger presented in FIG. 1, viewed from one end, and

FIG. 4 shows another embodiment of the invention in sectional view, as seen in the longitudinal direction of the tube.

In the case illustrated by FIGS. 1, 2 and 3, to the body tube 1 of the ice auger has been attached one single ice-removing helix 2 and to the end of the body tube, by screw attachment 4, a detachable blade 3, which comprises a cutting head manufactured by bending from a sheet blank and sharpened on one or two edges, and to which has been attached e.g. by welding, a supporting element 5 fitting into the body tube 1. This supporting element may be a dowel or a tubular piece or sleeve of lighter construction, which has been secured to the end of the body tube 1 by the screw 4 so as to be unturnable. The supporting element or sleeve 5 may furthermore be provided with a plug 9 which has been suitably dimensioned and the purpose of which is to prevent water from entering the body tube and the sleeve, and which thus prevents their interiors rusting and the freezing of water within them.

An essential part of the invention is the fact that the blade 3 has been provided with a fork 6, between the lips or jaws of which the end 7 of the helix 2 is guided to enter, whereby the blade and the helix together form a continuous helical surface, which has no screws, nuts or shoulders slowing down the passage of ice.

Fitting of the blade 3 in its place on the end of the body tube 1 is simply accomplished by first pushing the plug 9 into the supporting element 5 and then pushing the supporting element 5 into the end of the tube 1 and thereafter fitting the end 7 of the helix 1 into the fork

6 of the blade 3. In order to facilitate such guiding of the helix end, one jaw of the fork 6 may be made to have greater length than the other, whereby it conveniently acts as a guiding surface. The end 7 of the helix 5 now rests against the bottom of the fork 6, and the blade remains properly seated during the boring process, when the auger is turned in the boring direction. For the potential securing of the blade one may use not only a screw 4, but equally one may use a nail, rivet or 10 a cotter pin with or without spring loading, whereby the blade is held in its place whatever the direction in which the auger is rotated. Of these alternatives, a spring cotter pin or spring ring 8 has been shown in FIG. 4.

15 The examples presented in the foregoing represent only a few of the embodiments of the invention, in which the blade has been attached to an ice auger having only one ice-removal helix. It is naturally possible to provide the blade with two forks, whereby it is suitable to be attached to an auger having two helices. The blade will then be held better than in the case illustrated by FIGS. 1 and 2, without securing, in its place, and replacement of a sharp blade for one that has become dull is still accomplished in an instant. Of course, 20 the blade may also be secured in its place in the manner described in the above, or one may employ any other quick-lock attachment previously known in itself.

I claim:

1. Improvement in an ice auger, comprising an axially extending body tube having a first end and a second end, at least one ice-removing helix fixed to and extending about said body tube from the first end thereof, said helix having a leading end located at the first end of said tube and a trailing end spaced from the first end thereof, a detachable blade having a leading end and a trailing end, a supporting element secured to said detachable blade and extending from its trailing end, said supporting element fitted into the first end of said body tube so that the leading end of said detachable blade extends outwardly from the first end of said body tube, wherein the improvement comprises that the trailing end of said detachable blade adjacent the first end of said tube has a fork formed thereon with the opening of the fork directed toward the leading end of said helix at the first end of said body tube, the leading end of said helix is seated within and against the bottom of said fork so that said blade and helix combine to form a continuous helical surface which has no fixing elements or shoulders slowing down the passage of the ice flow, and a locking element for securing said supporting element to said body tube at a position spaced from the first end thereof so that said blade cannot be turned relative to said body tube.

2. Ice auger according to claim 1, characterized in that of the jaws of the fork one is longer than the other in order to facilitate the task of guiding the leading end of the helix into its place.

3. Ice auger according to claim 1, characterized in that the element for securing the blade to the body tube is a screw.

4. Improvement in an ice auger, comprising a body tube with at least one ice-removing helix and a detachable blade which includes a supporting element fitted into the end of said body tube, wherein the improvement comprises that said blade has at least one fork provided thereon and the end of said helix rests against the bottom of said fork, so that said blade and said helix

3,760,890

3

together form a continuous helical surface which has no fixing elements or shoulders slowing down the passage of the ice flow, said supporting element of said blade which fits into the end of said body tube is a tubu-

4

lar piece, and a plug fitted into said supporting element for the purpose of preventing the entry of water therethrough.
